DESIGN FOR A NONGLARE REFLECTOR

William L. Bear and George R. Walker,
Dayton, Ohio

Application November 5, 1936, Serial No. 65,718

Term of patent 14 years

To all whom it may concern:

Be it known that we, William L. Bear and George R. Walker, citizens of the United States, residing in the city of Dayton, county of Montgomery, and State of Ohio, have invented a new, original, and ornamental Design for Non-Glare Reflectors, of which the following is a specification, reference being had to the accompanying drawing, forming part thereof.

The figure is a perspective view of a non-glare reflector, showing our new design.

We claim:

The ornamental design for a non-glare reflector, as shown.

WILLIAM L. BEAR.
GEORGE R. WALKER.
